UNITED STATES PATENT OFFICE

2,191,331

ELECTRIC INCANDESCENT LAMP

Johannes A. M. van Liempt, Eindhoven, Netherlands, assignor to General Electric Company, a corporation of New York

Application December 12, 1938, Serial No. 245,281
In the Netherlands December 31, 1937

3 Claims. (Cl. 176—39)

My invention relates to electric incandescent lamps generally, and more particularly to support members for the metal filaments of incandescent lamps.

5 Electric vacuum-type incandescent lamps in which the filament is carried by the lead-in wires and also by one or several supports consisting of small hooks or eyelets, have the disadvantage that these eyelets conduct away a part of the 10 energy supplied to the filament in the form of heat as a result of which the filament, particularly at the points of support, adjusts itself to a somewhat lower temperature, a fact which naturally has a detrimental influence on the efficiency of the lamp.

An attempt has been made to overcome this disadvantage by making the eyelets of carbides, or by providing a metal core with oxides. However, it has been found that these known constructions present very many difficulties so that they have never been used in practice. In this connection it should be remembered that the manufacture of incandescent lamps is a mass production in which it is generally highly undesirable to make the manufacture of one part of a lamp so complicated that the entire manufacturing process suffers therefrom. The use of eyelets of the type indicated above cannot be carried out in practice. An eyelet made of carbide, for instance, must be baked separately, and the finished eyelets are too brittle to be placed in the intended glass part of the lamp by means of machines. Furthermore, wires which are covered with the materials that have been suggested heretofore have proved to be unsuitable because it is difficult to coat the materials on the core and because, in addition, they break when bent or formed into the shape of eyelets.

In a vacuum-type electric incandescent lamp, 40 according to the invention, in which the filament, of tungsten for example, is carried by one or more support members or eyelets as well as by the lead-in wires, these eyelets are made of a metal core and the layer or coating provided thereon 45 consists of a semi-conductor having a melting point of more than 2700° C. The metal core, for instance molybdenum wire, may be provided, in a reducing atmosphere, with the particular semi-conductor which is deposited from the gaseous phase. Due to the fact that the melting point of the particular semi-conductor is more than 2700° C. (and, therefore, above the temperature which is normally assumed by the filament located in the lamp), the covering layer is, under 50 the given circumstances, inert with respect to

the material of the filament. Tests have shown that as a result of the lower heat losses due to the coating of the eyelets with a thin layer of refractory semi-conducting material, an improvement in efficiency of approximately four per cent is obtained in the lamp according to the invention, as compared with lamps of otherwise similar qualities in which the eyelets have not been coated with such a layer.

5 The nitrides of a metal, which nitrides have a melting point of more than 2700° C., are very suitable for use as the semi-conductors, according to the invention. As examples, the following may be mentioned:

	Melting point, °C.
Titanium nitride	2930
Zirconium nitride	2930
Tantalum nitride	2800

20 Furthermore, carbides of metals can also be used according to the invention, which carbides have a higher melting point than the corresponding nitrides. Some examples of these carbides are:

	Melting point, °C.
Titanium carbide	3400
Zirconium carbide	3400
Tantalum carbide	4000

25 The above-mentioned conductors have the advantage that they can readily be placed on a metal core. For instance, a molybdenum wire may be provided with a layer of titanium nitride by leading this wire, in the heated state, through a current of well-dried and oxygen-free mixing gas in which there is mixed titanium chloride vapor. In this manner it is possible to provide a molybdenum wire, running off a spool in the above-mentioned atmosphere, with a thin layer of titanium nitride, and to rewind it on another spool. The wire prepared in that manner can be 30 worked without any difficulty and in the same way as the normal molybdenum wire in an eyelet-inserting machine; in other words, the supporting wires or eyelets can be placed in the intended glass part of the lamp by machine, while 35 the wire, particularly when the thickness of the layer is not too great, can be bent into the shape of eyelets without causing the layer or coating to break off or loosen. The vacuum-type coiled filament lamps equipped with these eyelets (for instance with 7 such eyelets) have an efficiency 40 which, for instance for the 220 volt 15 watt size, is approximately five per cent higher than that of the corresponding lamps in which the eyelets consist of the same total thickness of metal wire 45

without a covering layer. Another advantage of these semi-conductors over other covering materials lies in the fact that these materials have a coefficient of expansion which is of the same order 5 of magnitude as that of the customary eyelet material (tungsten or molybdenum) so that the layer will not tend to break off when subjected to temperature changes.

The invention is advantageous both in vacuum-type lamps with straight filament and also in vacuum-type lamps with coiled filaments. Because the filament in the latter type is much shorter than in the former type, or rather because the filament length between two hooks is in 15 this case always shorter, the advantage is the greatest in this case. In the vacuum-type lamps with coiled filaments, the advantage will be greater the thinner the coil is.

For a further understanding of the invention 20 reference may be had to the drawing which is a perspective view of a standard incandescent lamp mount in which may be incorporated support wires or eyelets of the type comprising my invention.

25 Referring to the drawing, the coiled filament 10 is supported at its ends by the lead-in wires 11-11. The filament is further supported intermediate its ends by the ends of support wires or eyelets 12 the opposite ends of which are

sealed in the upper end of the glass arbor 13. The said supports or eyelets 12 consist of metal wires (molybdenum or tungsten, for example) coated, in accordance with my invention, with a refractory semi-conductor, such as the nitride 5 or carbide of titanium, zirconium or tantalum.

What I claim as new and desire to secure by Letters Patent of the United States is:

1. In an electric incandescent lamp comprising a metal filament supported by lead-in wires 10 and one or more eyelets, said eyelets consisting of a metal core wire having thereon a coating consisting of a semi-conductor having a melting point in excess of 2700° C.

2. In an electric incandescent lamp comprising a metal filament supported by lead-in wires and one or more eyelets, said eyelets consisting of a metal core wire having thereon a coating consisting of one of the metallic compounds selected from the group consisting of nitrides and 20 carbides having a melting point above 2700° C.

3. In an electric incandescent lamp comprising a metal filament supported by lead-in wires and one or more eyelets, said eyelets consisting of a metal core wire having thereon a coating 25 consisting of one of the metallic compounds selected from the group consisting of nitrides and carbides of titanium, zirconium and tantalum.

JOHANNES A. M. VAN LIEMPT.
